PETER BACHER, OF CANTON, OHIO, ASSIGNOR OF ONE-THIRD TO ALBERT HOEFFER, OF HAMMONTON, NEW JERSEY, AND ONE-THIRD TO JOHN YEMIKER, OF AKRON, OHIO.

RAILWAY-JOINT.

1,133,694.

Specification of Letters Patent. Patented Mar. 30, 1915

Application filed July 28, 1914. Serial No. 853,600.

To all whom it may concern:

Be it known that I, PETER BACHER, a citizen of the United States, residing at Canton, in the county of Stark and State of Ohio, have invented certain new and useful Improvements in Railway-Joints, of which the following is a specification.

My invention relates to improvements in railway joints in which rail clamping devices are employed, whereby the railway rails are held in proper alignment.

The objects of the present invention, are, first, to provide clamp bars, one of said clamp bars adapted to bridge the joint between the ends of the two adjacent rails, second, to provide means for automatically drawing the clamp or splice bars against the webs of the railway rails, and third, to hold against displacement the means whereby the rails are clamped.

These objects, together with other objects readily apparent to those skilled in the art, I attain by the construction illustrated in the accompanying drawings, although my invention may be embodied in a variety of other mechanical forms, the construction illustrated being chosen by way of example.

In the accompanying drawings, Figure 1 is a perspective view. Fig. 2 is a detached perspective view of the rail supporting flange, clamp flange and clamp jaws. Fig. 3 is a detached perspective view of the bridge clamp. Fig. 4 is a transverse section taken through one of the railway rails, the clamp plates and clamping jaw and ball holding bar. Fig. 5 is a transverse view of the joint taken on a plane between the clamp jaws. Fig. 6 is a section taken on line 6-6, Fig. 4.

Similar numerals of reference indicate corresponding parts in all the figures of the drawing.

In the accompanying drawing, 1 represents the railway rails which are of the usual construction, except the ordinary elongated apertures to receive the clamping bolts are dispensed with, otherwise the rails are of the usual style.

Upon the wheel flange side of the railway rails and in contact with the rails is located the flange 2, which flange is so formed that it will come in contact with the vertical webs of the rails and between the underside of the rail tread 3 and the rail base flange 4 as best illustrated in Figs. 4 and 5. With the flange 2 is preferably formed integral the

rail support or base 5 and the spaced extended jaws 6, said jaws being spaced apart as illustrated and as illustrated four jaws are shown, it being a question of judgment as to the number of jaws employed in actual use.

Upon the opposite side of the railway rails from that upon which the flange 2 is seated is located the bridge flange, which bridge flange is made up of the tread portion 7, the contact flange portion 8, the rail supporting base 9 and the grooved flange 10. These various parts are preferably formed integral and constitute what might be termed a splice or fish plate. The flanges 10 are inclined outward or away from the contact flange 8 and are so formed for the purpose of producing a wedge action as herein-after described.

The flanges 10 are each provided with the semi-circular grooves 11 formed upon the outer inclined edges of said flanges. The jaws 6 are located at the outer ends of the lateral extensions or bars 12 and are also inclined downward and provided with semi-circular grooves 13. When the various parts are properly assembled the flanges 10 and the jaws 6 will be opposite each other as best illustrated in Fig. 6 and when so located the semi-circular grooves will be in position to hold the balls 14. It will be understood that by inclining the jaws and flanges, a wedge shaped opening or space will be formed or produced as illustrated in Fig. 4 by means of the inclination of the jaws and flanges 6 and 10 the balls 14 will come in contact with said jaws and flanges, thereby having a tendency to draw or move the jaws and flanges apart or away from each other which action in turn clamps the opposite flanges 9 located upon the opposite sides of the railway rails snugly against said railway rails and clamp said railway rails between the opposing flanges.

For the purpose of preventing any accidental displacement of the balls 14 a guard or safety plate 15 is provided, which plate is preferably formed T-shaped in cross section, the angled portion or web 16 being for the purpose of holding the balls against upward movement, and for the purpose of proper contact the edge of said web 16 is provided with the groove 17 which groove provides means whereby the balls can be better held against upward movement.

For the purpose of holding the safety plate in proper relationship a bolt 18 is provided, which bolt is formed of sufficient length to pass through the safety plate and the rail support base and extend a short distance below said base, so that the spring 19 may be located around said bolt and held in place by means of a cotter 20 or its equivalent.

10 The object of the spring 19 is to move the bolt 18 downward, thereby at all times holding the safety plate 15 in proper contact with the balls 14. It will be understood that by the movement of trains upon the 15 rails more or less vibration takes place and by reason of said vibration, the balls 14 will be jarred downward, thereby automatically and under all circumstances producing a clamping action upon the opposing splice 20 plates or fish bars referred to as opposing flanges.

For the purpose of preventing the usual clicking of the wheels of locomotives and cars as they pass over the joints the bridge 25 portion 7 is so formed that it will receive the tread flange of the wheels and in order to prevent any jarring said bridge portion should be very slightly beveled or curved upon its top or upper face so that said 30 bridge portion will carry the wheels over the joint, the tread portions of the wheel riding upon the bridge portion and will come on to and leave said bridge portion without any jar or jolting. For the purpose 35 of producing a close joint as between the edges of the rails 1, the tread or bridge portion is provided with an overhanging lip or flange 21.

For the purpose of providing room for 40 the jaws to come in proper relationship with reference to the flanges the base 9 should be provided with the notches or recesses 22 so that the jaws 6 can be brought into said notches or recesses. Another purpose of 45 providing the notches is to better hold the rail contact flanges against relative end movement with reference to each other.

It will be understood that by my peculiar arrangements the rails are free to expand 50 and contract there being no bolts through the rails, thereby allowing the slipping action as between the rails and clamps which is common by reason of the usual contraction and expansion.

55 I have described the means for forcing the flanges and jaws apart as balls which I consider the most practical, but I do not desire to be confined to the exact shape of the means for forcing the flanges and jaws 60 apart.

Having fully described my invention what I claim as new and desire to secure by Letters Patent, is:

65 1. In a railway joint, the combination of railway rails, a plate adapted for contact

with the vertical webs of said rails, a base flange adapted to support the railway rails, said base flanges provided with lateral extensions, jaws located at the outer ends of the extensions, said jaws provided with grooves, a bridge plate provided with flanges having grooves and a series of balls located between the flanges and jaws.

2. In a railway joint, the combination of railway rails, a plate adapted for contact 75 with the vertical webs of said rails, a base flange adapted to support the railway rails, said base flanges provided with lateral extensions, jaws located at the outer ends of the extensions, said jaws provided with 80 grooves, a bridge plate provided with flanges having grooves and a series of balls located between the flanges and jaws, and means for holding the balls against displacement.

3. In a railway rail joint, the combination of railway rails, splice plates located upon opposite sides of the railway rails, one of said splice plates constituting a bridge, the bridge plate provided with grooved flanges 90 inclined downward and outward, inclined jaws provided with grooves, balls located in the grooves of the inclined jaws and flanges, said balls adapted to move the flanges and jaws apart.

4. In a railway joint, the combination of railway rails, connecting plates provided with rail supporting faces, one of said plates provided with grooved jaws and the other with grooved flanges, the edges of said 100 flanges and jaws inclined, balls located between the jaws and flanges.

5. In a railway joint, the combination of railway rails, connecting plates provided with rail supporting faces, one of said plates 105 provided with grooved jaws and the other with grooved flanges, the edges of said flanges and jaws inclined, balls located between the jaws and flanges, and a guard plate adapted for contact with the balls.

6. In a railway joint, the combination of railway rails, connecting plates provided with rail supporting faces, one of said plates provided with grooved jaws, and the other with grooved flanges, the edges of said 115 flanges and jaws inclined, balls located between the jaws and flanges, and a guard plate adapted for contact with the balls, and means for holding the guard plate in contact with said balls.

7. In a railway joint, the combination of railway rails, rail connecting plates provided with rail supporting bases, one of said bases provided with jaws and the other with flanges, said flanges inclined toward the 125 jaws, means located between the jaws and flanges adapted to separate said jaws and flanges.

8. In a railway joint, the combination of railway rails, rail connecting plates pro-

vided with rail supporting bases, one of said bases provided with jaws and the other with flanges, said flanges inclined toward the jaws, means located between the jaws and flanges adapted to separate said jaws and flanges, and a guard plate adapted to rest upon the means for separating the flanges and jaws.

In testimony that I claim the above, I have hereunto subscribed my name in the presence of two witnesses.

PETER BACHER.
